UNITED STATES PATENT OFFICE.

FREEMAN HANSON, OF HOLLIS, ASSIGNOR OF ONE-HALF TO HERBERT G. BRIGGS, OF PORTLAND, MAINE.

RAILWAY-CAR VENTILATOR.

SPECIFICATION forming part of Letters Patent No. 368,148, dated August 9, 1887

Application filed April 23, 1887. Serial No. 235,922. (No model.)

To all whom it may concern:

Be it known that I, FREEMAN HANSON, residing at Hollis, in the county of York and State of Maine, have invented certain new and useful Improvements in Railway-Car Ventilators; and I do hereby declare that the following is a full, clear, and exact description of the invention, which will enable others skilled in the art to which it appertains to make and use the same.

Figure 1 is a perspective view showing the monitor roof of a railroad-car provided with this invention. Fig. 2 is a plan view of the monitor roof, a part removed, showing, generally, the internal structure as well as operation of this invention. Fig. 3 is a longitudinal central section of the roof. Fig. 4 is a central cross-section through the wind-wheels and fan. Fig. 5 is a detail of the longitudinal foul-air tube when the end of the monitor roof is curved downward. Fig. 6 is a detail showing the anti-friction rollers of the journals for the fan.

Same letters of reference in the several figures indicate corresponding parts.

This invention belongs to that class known as "railroad-car ventilators;" and the novelty in the present instance consists in the construction and combination of the several parts, whereby in a simple and economical structure a very efficient and durable means for ventilating is provided, all as will now be more fully set out and explained.

In the accompanying drawings, the car A is provided with the usual monitor roof B. Lengthwise above this is placed the ventilating structure, which consists of the central chamber, C, the chambers or passages D, one on each side of said central chamber, and the longitudinal foul-air tube E, passing through and communicating with the said central chamber and the valves which regulate the flow of air through the said side passages and tube. The roof of the monitor having numerous perforations, a, the foul air inside of the car is drawn through these perforations inside the chamber C through the openings e' by means of the fan F, centrally situated, one half of which rotates within the longitudinal tube E. The other half of the fan rotates within a shield, e², provided at its sides, where it fits over the fan's shaft, with ports e', which per-

mit the free passage of air from the central chamber, C, into the longitudinal tube E.

The fan is propelled when the car is in motion by means of the wind-wheels f f on the respective ends of its shaft f', and respectively located on either side of the chamber C in the chambers D D. The wind reaches these wheels through the open ends d of said chambers. The foul air, being thus drawn from the upper part of the car into chamber C, is sucked through the ports a, and is thence forced into the longitudinal tube E, and through it out of its rear end. The forward end of the tube E is closed by the flap-valve e automatically or by the rod e². There is such a valve at the rear of the tube, which is open when the fan is in operation.

The speed with which the fan F is operated can be regulated with the utmost nicety by means of the valves d' over the ports d in the ends of the side chambers, D. These valves can be opened wide, so as to make flaring mouths to the chambers, or be partly closed, or the valve on one side can be opened and the other closed. By a suitable manipulation in this general way of these valves any desired opening can be provided and any desired speed for the fan-wheel be thus obtained. Each of said valves is operated by the trainman from the inside of the car by means of the valve-rods d'. The valve d' is provided at one side with sockets closed at the top, into which the rods d' fit. This construction obviates all danger of rain leaking through about the bearings of the rods d'.

When the cars are at a station, the doors being usually wide open, there is no special need that the apparatus should be at work. When the train is in motion, especially in cool weather and with a crowded car, the necessity of the operation is felt.

This apparatus is particularly valuable for sleeping-cars, as it affords the very best facilities to draw off the impure air without creating any draft, a point of special value in a sanitary point of view.

This structure, as will be noticed from the foregoing description, is very simple and very durable, and not at all expensive. It can be applied to any car having the monitor roof, and in its exterior forms, &c., can be made a very ornamental addition to the roof. In ap-

plying the device when building a car, the structure can be so merged in the roof as not to cause any special change in the general appearance of the roof.

5 Having now described my invention, what I consider new, and desire to secure by Letters Patent, is—

1. In combination with a perforated roof of a monitor car, a central chamber, C, communicating with the interior of the car by the perforations in said roof, a longitudinal air-tube extending through said chamber and communicating therewith, and having valves in each end, and fan-wheels whereby the foul air is drawn from the interior of the car and forced through said longitudinal tube.

15 2. In combination with the car A, having its roof perforated at a, the longitudinal chambers C and D, the tube E, the valves e, and the fan F and wind-wheels f, substantially as described.

20 3. In railroad-car-ventilating apparatus, an external chamber communicating with the interior of the car, and a fan therein and wind-wheels operating the same, combined with valved air-passages leading to said wind-

wheels, whereby the speed of revolution of the wheels and fan can be regulated at will, substantially as described.

4. In combination with the longitudinal main chamber and its fan, and the foul-air tube E, having valves in each end, the side chambers having the wind-wheels operating the fan, said chamber having flaring ends provided with valves operated from the interior of the car.

35 5. In a railway-car, substantially as described, a ventilating apparatus consisting, essentially, of a perforated roof, a chamber over said roof, a foul-air tube passing through said chamber and communicating therewith, a fan-wheel for drawing the air from the car and forcing it into said tube, and wind-wheels for operating said fan, substantially as described.

40 In testimony that I claim the foregoing as my own I have affixed my signature in the presence of two witnesses.

FREEMAN HANSON.
